BOBBIN-IDENTIFYING DEVICE FOR
WINDING MACHINES

Winthrop Sanford Warren, Newtonville, Mass.,
and Walter Victor Jacobson, Apponaug, R. I.,
assignors to Universal Winding Company, Bos-
ton, Mass., a corporation of Massachusetts

Application September 11, 1941, Serial No. 410,452

20 Claims. (Cl. 242—1)

This invention relates to winding machines for winding yarn, thread and similar textile materials into packages, such as cops, bobbins, pirns and the like. More specifically, the invention relates to the earmarking or identifying of textile packages as they are produced on the winding machine.

In the present specification and claims the term "yarn" is employed to indicate all kinds of attenuated material and the term "bobbin" is used to designate the wound package whatever its form or character.

It is a common practice in textile mills to identify filling yarn by marking the bobbins with crayon or chalk to indicate different types and counts of the yarn and also to identify the machine or department in which the yarn is processed or handled. The operator of the machine marks the yarn on the bobbin by drawing a piece of chalk or crayon across the surface of the wound bobbin, but this operation has certain disadvantages as it is liable to cause the chalk dust to infiltrate into the mechanism of the machine to interfere with its proper functioning. Moreover, it is impractical to apply chalk or crayon marks to certain types of filling such as worsted or woolen yarn.

The practice of marking bobbins for identification of the yarn is for the purpose of preventing mixed counts or different twists of filling from going to the same loom and becoming incorporated in the fabric. In such case the difference in the size or twist of the filling does not become evident until the cloth is woven and therefore often results in spoilage or seconds in the product of the mill. When the bobbins are properly marked the weaver can discover if mixed yarn is furnished to the weave room and place the responsibility in the winding room or other department of the mill where the yarn is processed or handled. In other instances, by applying several distinguishing marks to the yarn on the bobbin its progress from the source can be followed and when poor or imperfect bobbins reach the weave room they can be traced to the machine in which they were wound or to the department in which the yarn was processed. In some mills different types or counts of yarn are wound on different spindles of the same machine and the bobbins may become mixed through carelessness of the operator, as by the dropping of bobbins on the floor or by incomplete emptying of the collecting boxes for one type of yarn before bobbins of another type are placed therein. Most mills handle more than one count of yarn at the same time and as the counts must be kept separate it is an object of the present invention to provide automatically-operated apparatus for earmarking or identifying the bobbins as they are produced in the winding machine by attaching an

identification tag or ticket thereto to prevent mixed counts from being woven in the loom; and further, to trace the steps in the processing of the yarn in different departments of the mill to correct defects or deficiencies in its manufacture.

Another object of the present invention is to provide an apparatus of the type indicated which is adapted to be applied to existing winding machines as an attachment.

Another object is to provide an apparatus of the type indicated which is adapted to feed a tag or ticket from a continuous strip thereof into position to be gripped between the winding yarn strand and bobbin and to sever the ticket from the remainder of the strip.

Another object is to provide an apparatus of the type indicated which is automatically-operated to apply the ticket in proper timed relation to the winding operation.

Still another object is to provide an apparatus of the type indicated which is reliable in operation to feed and sever the tickets and of simple and compact construction to adapt it for economical manufacture.

Further objects of the invention are set forth in the following specification which describes a preferred form of the apparatus, by way of example, as illustrated by the accompanying drawings. In the drawings:

Fig. 1 is a side elevational view of a portion of a winding machine incorporating the novel features of the present invention;

Fig. 2 is a plan view of one spindle of the winding machine showing the relationship of the ticket-applying means with respect thereto;

Fig. 3 is a fragmentary end view of the ticket-applying means and bobbin showing the manner in which the ticket is fed into position with respect to the winding yarn strand and the bobbin;

Fig. 4 is a view similar to Fig. 3 showing the manner in which the ticket is gripped between the winding yarn strand and the bobbin to attach it to the latter;

Fig. 5 is a rearward elevational view of the ticket-applying device shown partially in section, and illustrating the ticket-feeding means in its inoperative position;

Fig. 6 is a view similar to Fig. 5 showing the relationship of the parts of the ticket-applying device when the electromagnet actuator is energized to advance the ticket-feeding means and ticket-strip gripped thereby;

Fig. 7 is a perspective view of the ticket-applying device with the parts shown in extended relation;

Fig. 8 is a diagrammatic view of the electric circuit for the electromagnet actuator of the ticket-applying means and the circuit-controller for controlling the operation of the ticket-apply-

ing means in timed relation to a winding operation; and

Fig. 9 is a view of a bobbin showing a ticket attached thereto in a somewhat different position from that illustrated in Figs. 2 and 6.

While the present invention may be applied to use with either manually-operated or automatic winding machines, it is herein described and illustrated in connection with an automatic bobbin winder of the type disclosed in the copending applications for United States Letters Patent, Serial No. 231,044, filed September 21, 1938, by C. D. Reynolds et al., now Patent No. 2,257,651 issued Sept. 30, 1941, and Serial No. 385,346, filed March 26, 1941, by C. D. Reynolds et al., now Patent No. 2,302,715 issued Nov. 24, 1942. The machines illustrated in these prior applications for patent are completely automatic in their operation to provide for donning empty cores or yarn-carriers, winding the yarn thereon, and doffing the bobbins as they are completed. It is therefore desirable that a machine of this type shall be further adapted for earmarking or applying indicia to the bobbins automatically to identify them after they have been delivered from the machine. On the other hand, it is to be understood that the present invention is not limited to use with automatic winding machines, but may be applied to other types of winders for labeling the bobbins before they are doffed.

Referring to the drawings, in Fig. 1 a portion of a winding machine is illustrated comprising a frame or casing 2, and projecting from bearings therein is a rotary winding spindle 3. The winding spindle 3 carries a cup-shaped member 4 at its outer end for receiving the head *h* of a wooden core or bobbin *b* such as used in either plain or automatic filling-changing looms. The opposite or tip end of the bobbin *b* is held in a similar recessed member 5 on a spindle 6 mounted free to rotate in a bearing sleeve 7 supported by an upright bracket 8 attached to the end of a horizontal arm 9 projecting forwardly from the side of the machine frame 2, see Fig. 2. In the type of machine illustrated herein the yarn *y* is wound on the core or wooden bobbin *b* by means of a thread-guide 10 which has a relative traversing motion axially of the bobbin and is advanced progressively longitudinally thereof to deposit the yarn in courses of cross-wound coils which overlap at their forward ends. Consequently, the bobbin *B* grows by longitudinal extension, being formed with a conical base, a cylindrical body portion and a tapered or conical tip end as indicated by dot-and-dash lines in Fig. 2.

The thread-guide 10 is carried on a reciprocable traverse-rod 15 mounted to slide longitudinally in a bearing in the frame or casing 2 with its outer end supported by an outboard bearing 16 carried on the bracket 8, referred to previously as the support for the spindle bearing-sleeve 7. The traverse-rod 15 is reciprocated longitudinally in its bearings by a suitable cam or similar means enclosed within the frame or casing 2 of the machine, but not herein illustrated as such traversing mechanism is well known to those versed in the art. The yarn *y* delivers from its source of supply, usually supported above the machine, but not herein shown, and feeds to the bobbin through an eyelet 17 in the thread-guide 10. Connected to the thread-guide 10 is a rotatable contact-disk or traverse-wheel 20 mounted on a sleeve-like nut 21 which is interiorly threaded to engage the screw-threads 22 on the traverse-rod 15. It will be understood that the

thread-guide 10 is positioned adjacent the rearward or butt end of the yarn-carrier or wooden bobbin *b* at the start of the winding and the traverse-wheel 20 is so related thereto that each time the guide makes a return stroke to the left, as viewed in Figs. 1 and 2, the periphery of the wheel will contact the yarn wound on the bobbin to turn the nut 21 through a part of a rotation to feed the guide forward to a slight extent along the traverse-rod. This method of advancing the layers of winding along the bobbin by the intermittent advance of the thread-guide is illustrated and described in the prior applications referred to above and well known to those versed in the art.

At the completion of the bobbin the thread-guide 10 will be positioned at the forward or tip end of the bobbin when at the furthermost limit of its forward stroke and at this point the guide, or a part connected therewith, engages a stop or abutment to move the latter to cause actuation of the stopping mechanism of the machine, this mechanism being employed generally in machines which require manual doffing and donning. In automatic machines such as described in the pending applications referred to above, the completion of the bobbin effects initiation of the operation of means for doffing the wound bobbin, donning an empty core or yarn-carrier, attaching the end of the yarn to the empty carrier, severing the yarn from the doffed bobbin, returning the thread-guide to initial winding position, and again starting the winding operation. The automatically-operated mechanism for performing these functions is described in the prior patent applications hereinbefore mentioned and is not referred to specifically herein as it forms no part of the present invention. Suffice it to state that as the wound bobbin *B* is doffed by releasing it from the driven winding spindle 3, it drops by gravity into a chute 23 arranged therebelow.

It is the common practice in winding filling bobbins to wind a few closely adjacent coils on the butt end of the core or carrier *b* at the beginning of the winding operation to form a bunch *X* which provides a reserve length of yarn in the shuttle to prevent "misspicks" when the filling is changed. The winding of such a bunch may be controlled by a separate thread-guide, commonly known as a bunch-builder, or the operation of the thread-guide may be restricted to wind with a short stroke at the beginning of the winding to cause the bunch to be wound, such devices being well known to those versed in the art.

In accordance with the present invention an identification tag or ticket *T* is attached to the bobbin by inserting it under the yarn strand *y* winding on the carrier *b* at the beginning of a winding operation to cause it to be gripped to the bobbin by the bunch windings. The ticket *T* as illustrated in the present drawings may consist in a length of paper strip detached from a continuous supply *t* and printed or marked to identify the particular yarn and/or winding unit on which it is wound. For example, the ticket *T* may have a particular color for indicating the count or size of the yarn with identifying indicia printed thereon, such as the characters A-8 illustrated in Fig. 2 of the drawings, for indicating the source of supply or the particular spindle on which the yarn is wound; or the reference character A may denote the machine on which the bobbin was wound and the numeral 8 indicate

the particular spindle of that machine unit. It may be desirable in some instances to further identify the characteristics of the particular bobbin, such as the twist of the yarn or the particular lot in which the yarn was dyed and any other characteristic which may be indicated by additional reference characters such as A-8-I.

As illustrated in Figs. 1 and 2 the ticket-strip *t* is coiled to form a roll 25 which is mounted to rotate on a support or bracket 26 attached to the casing 2 of the winding machine. The supporting bracket 26, shown in Fig. 1, is of bifurcated form having spaced arms for receiving the roll 25 of paper strip *t* therebetween and having a spindle 27 extending between the arms and through the center of the roll to adapt the latter to rotate thereon. To apply the roll 25 for feeding the ticket-strip *t* it is only necessary to insert the spindle 27 through the arms of the supporting bracket and center of the roll. Adjacent the bottom of the bracket 26 is an elbow-shaped arm 28, see Figs. 1 and 2, under which the strip *t* is inserted to guide it off from the roll 25.

Mounted on the machine frame or casing 2 adjacent the bracket 26 is a ticket-supplying mechanism 30 adapted to feed the ticket-strip *t* a distance equal to the length of a ticket *T* to be applied and arranged to sever the ticket from the remainder of the strip. The ticket-applying mechanism 30 comprises a channel-shaped base 31, see Fig. 7, having a bottom wall 34, side walls 32 and 33 extending upwardly from the bottom wall and a rearward end wall 35. Preferably, the base 31 is made from a single piece of sheet-metal folded into channel-shape with the inner side wall 32 and end wall 35 considerably higher than the side wall 33. The base 31 is mounted on the machine by means of a bracket 36, see Figs. 1, 2 and 5, bolted to the end wall 35 and having an angular portion clamped between the bracket 26 and a ledge on the machine frame 2. The bracket 36 as herein shown is so constructed and arranged as to position the open end of the channel-shaped base 31 at an acute angle to the axis of the bobbin *b* adjacent the butt end of the latter, see Fig. 2, and slightly inclined downwardly toward the axis of the bobbin, see Fig. 1. It is to be understood, however, that the base 31 may be mounted in any suitable relation to feed a ticket *T* into position to be bound to the bobbin by the coils of yarn wound thereon. For example, the base 31 may be placed parallel to the axis of the bobbin to provide for applying the ticket *T* in line with the barrel of the bobbin *b* as illustrated in Fig. 9.

A pair of curved springs 37 and 38 are provided at the rearward end of the base 31 extending downwardly and forwardly, see Fig. 5, to adapt the ticket-strip *t* to feed therebetween. The spring 37 is attached to the upper portion of the end wall 35 of the base 31 and extends downwardly and forwardly therefrom to overlie the bottom wall 34 thereof. The spring 38 has its upper end attached to an angular bracket 39 fastened to the side wall 32 of the base 31 and extends downwardly and forwardly therefrom with its free end converging toward the free end of the spring 37. Thus, the pair of springs 37 and 38 provide a guide for the ticket-strip *t* and also act to tension the strip when the latter is fed therethrough to hold it against rearward movement. A leaf-spring 40 is attached at one end to the outside face of the side wall 33 of the base 31 and shaped with an offset curved por-

tion 41 at its opposite end forming a detent which projects inwardly through a suitable opening 42 adjacent the rearward end of the side wall.

Feeding means for the ticket-strip *t* are mounted for movement longitudinally of the base 31, being adapted to grip the strip during movement of said means in one direction and to release the strip during movement in the opposite direction. The gripping and feeding means comprise among other elements a channel-shaped slide 43 having a bottom wall 44 and spaced side walls 45 of such dimensions as to adapt the slide to fit closely within the sides of the channel-shaped base 31. As illustrated most clearly in Fig. 7, the forward portions of the side walls 45 of the slide 43 are of reduced height to provide vertical shoulders 46 intermediate the ends of the slide. A guide-bar 47 is attached to the rearward side 32 of the base 31 with its bottom edge 20 overlying the upper edge of one of the side walls 45 of the slide 43 to restrain the latter from rising in the base while guiding its longitudinal sliding movement therein. The slide 43 is limited in its rearward movement by the engagement 25 of its rearward end with the end wall 35 of the base 31 and its forward movement is limited by the engagement of the shoulders 46 intermediate its ends with lugs 48 extending inwardly toward each other from the forward edges of the 30 side walls 32 and 33 of the base.

Referring to Fig. 7, the outer side wall 45 of the slide 43 has a vertical groove 49 adjacent its rearward end which is adapted to be engaged by the detent 41 projecting inwardly through the opening 42 in the side wall 30 of the base 31 and the bottom wall 44 of the slide has a sharpened cutting edge 51 on the forward side of a transverse slot or opening 50 therein. Welded or otherwise attached to the bottom wall 44 of the slide 43 at its rearward end is a leaf-spring 52 having its forward end curved upwardly slightly above the opening 50. The spring 52 is of relatively thin stock to adapt its upwardly curved end to yield to be depressed into the opening 50 in the bottom wall 44 of the slide 43. Projecting inwardly from one of the side walls 45 of the slide 43 is a lug 53 which functions for a purpose as explained hereinafter. As will be noted by reference to Fig. 7, the forward corner of the slide 43 is cut away and gradually rounded with the side wall 45 terminating short of the end of the slide to permit free delivery of a ticket *T* therefrom as the bobbin *B* rotates with the ticket bound thereto.

Mounted to rock on the slide 43 is a gripping member 55, see Figs. 5 and 6, in the form of a bell-crank-lever having a horizontally-extending arm 56 overlying the bottom wall 44 of the slide 43 and a vertically-extending or upright arm 57. The gripping member 55 is pivotally mounted on a pin 58 extending between the side walls 45 of the slide 43 and through ears 59 folded upwardly from its horizontally-extending arm 56. Referring to Fig. 5, the forward portion of the horizontal arm 56 of the gripping member 55 normally overlies the upwardly bent end of the spring 52, being curved downwardly with its forward edge 60 constituted as a knife or cutter for cooperating with the cutting edge 51 at the side of the opening 50 in the bottom of the slide 43 to function as shears. A resilient finger 61 is attached to the upper face of the horizontal arm 56 of the gripping member 55 by means of a screw 62 with its forward end curved downwardly toward the bottom wall of the slide 43 forwardly

of the opening 50 to overlie a slight recess 63 formed therein.

The vertically-extending arm 57 of the gripping member 55 is curved rearwardly at its upper end and projecting forwardly from its side is a finger 65 which may be formed integral therewith or attached to its forward face by an extension 64 welded or brazed thereto as shown in Fig. 7. The finger 65 overlies the upper edge of the wall 33 of the base 31 to adapt it to engage therewith to limit the rocking movement of the gripping member 55 on the slide 43 in counterclockwise direction as viewed in Fig. 5 during the major portion of the forward stroke of the slide. As will be noted by reference to Fig. 7, the forward end of the side wall 33 of the base 31 is beveled off or inclined downwardly, as indicated by the reference character 66, to permit an added rocking movement of the gripping member 55 in counterclockwise direction at the end of the forward stroke of the slide 43. The rocking movement of the gripping member 55 on the slide 43 in clockwise direction, as viewed in Fig. 5, is limited by the engagement of the resilient finger 61 with the lug 53 projecting inwardly from the side wall 45 of the slide.

The gripping member 55 is rocked on the pivot-pin 58 and the slide 43 reciprocated with respect to the base 31 by the energization of an electromagnet having a U-shaped magnetic frame 70 attached to the side wall 33 of the base. Mounted on one arm 71 of the frame 70 is an electromagnet winding in the form of a coil 72, the wall 33 of the bracket 31 being recessed to provide an opening for the bottom portion of the coil. The opposite arm 73 of the frame 70 has a bifurcated end for receiving the reduced end 74 of an armature 75. The armature 75 is pivotally mounted on the arm 73 of the frame 70 by means of a pin 76 extending through the bifurcations and the reduced end 74 of the armature. The lower free end of the armature 75 extends forwardly in the form of a plunger 77, see Fig. 7, the bottom face of which is of arcuate shape to adapt it to cooperate with the corresponding arcuate upper face of the arm 71 of the frame 70. The armature 75 is adapted to be rocked in counterclockwise direction away from the arm 71 of the frame 70 by means of a hairpin-shaped spring 78, see Fig. 5, coiled about its pivot-pin 76 with one end engaging the arm 73 of the frame 70 and its opposite end engaging the armature 75. Upon energization of the magnet the plunger 77 is drawn into the coil 72 by magnetic attraction causing the armature 75 to rock on its pivot-pin 76 in clockwise direction as viewed in Figs. 5 and 6.

A sheet-metal member 83 mounted on the side of the armature 75 by means of screws 82 has a laterally offset intermediate portion 84 extended in a forwardly-projecting arm 85 which terminates in a downwardly inclined finger 86. Pivotaly mounted on a pin 92 projecting from the arm 85 of the member 83 is an auxiliary arm 87 having lugs 88 and 89 projecting rearwardly therefrom for engagement with the opposite sides of the arm 85 to limit its pivoting movement in each direction. At the end of the auxiliary arm 87 is a finger 90 which is offset laterally to aline it with the finger 86 on the arm 85 in spaced relation thereto, see Fig. 7. The arm 87 is adapted for limited rocking movement in relation to the arm 85, but is yieldingly urged in clockwise direction with respect to the arm 85, see Fig. 5, by means of a spring 75

91 coiled about the pivot-pin 92 with one end bearing against the finger 90 and its opposite end bearing against the arm 85. The member 83 is so constructed and arranged as to position the fingers 86 and 90 on opposite sides of the upright arm 57 of the gripping member 55 when the slide 43 is in its rearmost position.

Upon energization of the magnet coil 72 to rock the armature 75 on its pivot 76 the finger 90 on the bracket 83 engages the rearward side of the upright arm 57 of the gripping member 55 to thereby rock the latter in counterclockwise direction to cause the resilient finger 61 to grip the ticket-strip *t* against the bottom wall of the slide 43. Since rocking movement of the gripping member 55 is limited by the engagement of its longitudinally-extending finger 65 with the upper edge of the wall 33 of the base 31, continued movement of the armature 75 in clockwise direction is translated into longitudinal sliding movement of the slide 43. Upon de-energization of the magnet coil 72 the spring 78 will rock the armature 75 in counterclockwise direction, at which time the arm 86 of the member 85 will engage the forward face of the upright arm 57 of the gripping member 55 to rock it in clockwise direction to release the ticket-strip *t* and return the slide 43 to initial position.

The energization of the magnet coil 72 may be controlled in any suitable manner, but preferably it is under the control of a controller of the type illustrated and described in the Reynolds et al. applications referred to above. Suffice it to state herein that the controller comprises a cam-shaft 96, see Fig. 8, having a cam 97 thereon for operating a switch 98 in an electric circuit including the magnet coil 72. Thus, at a particular time during the rotation of the shaft 96 the cam 97 closes the switch 98 to energize the magnet coil 72. The controller cam-shaft 96 is adapted to rotate through one complete revolution and has a series of cams as indicated in Fig. 8 for controlling branch circuits in timed sequence to arrest the winding operation upon completion of a bobbin, don an empty bobbin *b*, start the winding of a new bobbin, and attach a ticket thereto. Fig. 8 illustrates parallel branch circuits adapted to control the donning of an empty bobbin *b* and the starting of a new winding operation. The circuit for controlling the donning of an empty bobbin *b* comprises a cam 100 on the control shaft 96, a switch 101 and a magnet winding 102, while the circuit for starting a new winding operation comprises a cam 103 on the control shaft 96, a switch 104 and a magnet winding 105. It will be understood that the cams 100, 97 and 103 are so arranged as to actuate the switches 101, 98 and 104 in timed sequence whereby an empty bobbin *b* is donned, a ticket *T* fed between the yarn strand *y* and the bobbin *b* and a new winding operation started to cause the ticket to be gripped between the coils of the winding strand and the bobbin. One form of the invention having been described in detail the mode of operation of the device is explained as follows:

A roll 25 of the ticket-strip *t* having the proper color and identifying indicia printed thereon is mounted on the bracket 26 between its bifurcated arms and the pin 27 inserted through the arms and center of the roll. It will be understood that a similar roll 25 having the proper identifying indicia is supplied to each unit of

the gang machine, only one spindle of which is shown in the present drawings. The end of the ticket-strip *t* is inserted between the converging springs 37 and 38 and the gripping member 55 and slide 43 of the ticket-applying means 30 and drawn therethrough until its end projects forwardly from the slide as illustrated in Fig. 2.

Considering that the machine is operating, upon completion of the winding of a bobbin *B* the thread-guide 10 will be at the outer end of the traverse-rod 15 and as the latter makes a forward stroke the guide, or a part attached thereto, will strike an abutment or other means to move the latter to set into operation the doffing and donning mechanisms of the machine. The various mechanisms for this purpose are under the control of electromagnets adapted to be energized by circuits which are closed by the several cams on the controller-shaft 96, indicated in the diagrammatic view, Fig. 8. The controller-shaft 96 is connected to rotate through a clutch or other means shown and described in the Reynolds et al. applications referred to previously herein. As the first step in the doffing and donning operation the spindle-cup 4 is retracted to release the wound bobbin *B* which drops by gravity into the chute 23. An empty bobbin or yarn-carrier *b* is then transferred into position between the spindle-cup 4 and the recessed member 5 on the opposed spindle 6 with the strand of yarn *y* trailing from the wound bobbin *B* and positioned between the spindle-cup and the butt end of the empty bobbin. The cam 100 on the controller-shaft 96 then acts to release the switch 101 to open the circuit to the electromagnet winding 102 to release the spindle-cup 4 whereby it is projected forwardly by means of a spring, not herein shown, to grip the empty bobbin between the cup and the recessed member 5 on the spindle 6; the yarn strand *y* being thereby clamped against the end of the bobbin. The winding spindle 3 is then started to rotate through the means of suitable clutch-devices, not herein shown, whose action is initiated by electromagnetic means, as described in detail in the pending application Serial No. 385,346 referred to above. As the winding spindle 3 is driven to rotate the bobbin *b* the trailing end of the yarn leading to the doffed bobbin is severed automatically and at this juncture the bunch-building means comes into action to restrict the traverse of the yarn as the thread-guide 10 is reciprocated by the traverse-rod 15 coincidentally with the rotation of the winding spindle.

Immediately the bobbin is gripped between the spindles 3 and 6 the cam 97 on the controller-shaft 96 functions to close the switch 98 to complete the circuit to the electromagnet winding 72 of the actuator for the ticket-applying means 30. Energization of the electromagnet winding 72 causes the armature 75 to be attracted and rocked in clockwise direction, as viewed in Fig. 5, to actuate the strip-feeding means to advance the strip *t* a distance equal to the length of a ticket *T*. This rocking movement of the armature 75 causes the finger 90 at the end of the arm 87 to engage the upright arm 57 of the gripping member 55 to rock the latter on its pivot-pin 58 and thereby press the forward end of its arm 56 against the ticket-strip *t* to grip it against the end of the spring 52 on the bottom wall 44 of the slide 43. During this action the slide 43 is restrained momentarily from longitudinal sliding movement along the base 31 by

the engagement of the detent 41 at the end of the yieldable spring 40 with the groove 49 in the side of the slide, see Fig. 7. The restraint of the movement of the slide 43 will cause the finger 90 to rock slightly against the tension of its spring 91, this yieldable action of the finger being designed to cushion the shock caused by the rapid movement of the armature 75 as it is rocked by the attraction of the magnet winding 72. It will be understood that the yielding action of the finger 90 is limited by the engagement of its lug 88 with the upper edge of the arm 85 carried on the armature 75. The gripping member 55 is limited in its rocking movement by the engagement of its forwardly-extending finger 65 with the upper edge of the side wall 33 of the base 31, and immediately this occurs the finger 90 on the armature 75 will cause the gripping member 55 to slide forwardly along the base 31. As the full force of the armature 75 is applied by the finger 90 against the upright arm 57 of the gripping member 55 to slide the slide 43 forwardly the detent 41 is released from the groove 49 in the side of the slide.

The forward movement of the slide 43 is limited to a distance equal to the length of the ticket *T* to be applied as the shoulders 46 on the side of the slide engage with the lugs 48 at the end of the base 31. As the slide 43 approaches this limit in its forward movement the finger 65 on the gripping member 55 will ride down the inclined or beveled edge 66 on the forward wall 33 of the base 31 to permit the gripping member to rock to a further extent in contraclockwise direction. This additional rocking movement of the gripping member 55 causes the forward end of its horizontal arm 56 to be forced downwardly across the cutting edge 51 on the side of the slot 50 in the slide 43 to sever a length of the strip *t* to form a ticket *T* which is held in extended position on the slide by the engagement of the resilient finger 61 therewith. During this latter rocking movement of the gripping member 55 the spring 52 therebeneath yields as indicated in Fig. 6 of the drawings. At this stage in the operation of the ticket-applying means the end of the spring finger 61 will overlie the top of the severed ticket *T* and press the latter into the depression 63 at the end of the bottom wall of the slide 43.

The ticket *T* severed from the strip *t* is thus held momentarily in position overlying the top of the bobbin *b* adjacent the base thereof as indicated in Figs. 3 and 6 of the drawings. At this juncture the end of the strand *y* has been clamped to the end of the bobbin *b*, as shown in Fig. 3, and the spindle 3 is started to rotate by connecting it to the drive through the medium of the magnet winding 105 as the switch 104 is closed by the cam 103 on the controller-shaft 96. The rotation of the bobbin *b* will draw the strand *y* across the top of the ticket *T*, as indicated in Fig. 4, to bind the ticket against the bobbin and cause it to be carried around therewith and withdrawn from the applying device 30. Now, as the rotation of the bobbin *b* continues the strand of yarn *y* leading from the thread-guide 10 will be wound around the bobbin overlying the ticket *T* as indicated by dot-and-dash lines in Fig. 6 to securely fasten it in place by the coils of winding in the bunch *X*. As the bunch *X* is completed the yarn *y* is released from the bunch-building means to allow the thread-guide 10 to traverse it to the full extent as indicated in Fig.

2 of the drawings to form the service winding on the bobbin *b*. The whole length of the ticket *T* will thus be bound around the bobbin *b* except for a slight portion at its end which is left projecting to display the indicia thereon. The indicia may comprise one or more characters which are duplicated at short intervals along the length of the strip *t* so that at whatever point the strip is severed there will be at least one set of characters showing as indicated in Figs. 2 and 9.

The cam *97* which controls the operation of the ticket-applying means is so constituted and its operation so timed as to cause it to release the switch *98* to open the circuit to the magnet winding *72* immediately the ticket *T* has been delivered to the winding bobbin. Consequently, the deenergization of the magnet winding *72* will effect release of the armature *75* to cause it to be rocked in counterclockwise direction under the action of the spring *78* to return it to its initial inoperative position shown in Fig. 5. During this rearward rocking motion of the armature *75* the finger *86* carried thereby will engage the upright arm *57* of the gripping member *55* to first rock the latter in clockwise direction on the slide *34* and thereafter slide the slide rearwardly until its end brings up against the wall *35* of the base *31* as the detent *41* is engaged with the groove *49* in the side of the slide, see Figs. 5 and 7. The rocking movement of the gripping member *55* in the manner last explained is limited by the engagement of the resilient finger *61* with the lug *53* on the side wall *45* of the slide *43*, see Fig. 5. The initial rocking movement of the gripping member *55* raises its arm *56* to release its end from the strip *t* so that it will pass over the strip *t* as the slide *43* returns to its rearward position; the strip *t* being meanwhile held from retrogressive movement by the gripping action of the two springs *37* and *38* with the forward end of the strip advanced slightly beyond the end of the base *31*, see Fig. 5. Consequently, the strip *t* will be fed forwardly again at the next operation of the gripping member *55* in the manner as previously explained. The machine will continue to operate in the manner explained to arrest the rotation of the winding spindle upon completion of each bobbin *B*, doff the wound bobbin, don an empty bobbin *b* and attach the strand thereto, with the present device acting in timed sequence to deliver a ticket *T* in position to be gripped to the bobbin by the winding of the strand thereon as the bunch winding is started.

It will be observed from the foregoing specification that the present invention provides a simple and compact device for automatically delivering tags, tickets or similar identifying elements and applying them to the bobbins as they are wound in the machine. The device is of such form and construction as to adapt it to be employed as an attachment for application to machines already in use by supplying the necessary electrical connections. The device is entirely automatic in its operation and reliable in performing its intended functions while being relatively inexpensive to manufacture.

While a preferred form of the device is herein illustrated and described, it is to be understood that its mechanism may be modified and its application to use may be varied without departing from the spirit and scope of the invention. That is to say, the ticket-serving device may be arranged to apply the ticket to the bobbin in different relationship from that herein shown, for

example by serving a gummed strip for attachment to the wooden base of the bobbin as the latter is gripped to the spindle-center or cup by which it is rotated. Therefore, without limiting ourselves to the exact arrangement and construction of the present device as herein shown and described, we claim:

1. In a machine for winding yarn into packages, in combination with the winding means, means for serving identifying tickets to the packages, and means for operating said serving means automatically at an intermediate stage of the winding.
2. In a winding machine, means for winding yarn to form a bobbin, and means for inserting an identification ticket between the winding yarn strand and the bobbin to cause the ticket to be gripped to the bobbin.
3. In a winding machine, means for winding a bobbin, means for applying an identification ticket between the winding yarn strand and the bobbin to cause the ticket to be gripped to the bobbin, and means for operating said ticket-applying means to apply a ticket in timed relation to the winding operation.
4. In a winding machine, means for winding bobbins, means for applying an identification ticket to each bobbin, said ticket-applying means acting to direct the ticket into position to cause it to be gripped between the winding yarn strand and the bobbin, and means for operating said ticket-applying means to apply a ticket in timed relation to the winding operation.
5. In a winding machine, means for winding a bobbin, means adjacent the bobbin for applying an identification ticket from a continuous strip of tickets to insert the ticket between the winding yarn strand and the bobbin to cause it to be gripped by the strand, and means for operating said ticket-applying means to apply a ticket in timed relation to the winding operation.
6. In a winding machine, means for winding a bobbin, means for mounting a continuous strip of tickets having identifying indicia thereon, means adjacent the bobbin for advancing the ticket-strip to position a ticket between the winding yarn strand and bobbin to cause it to be gripped to the bobbin with its end projecting from the winding, and means for operating said ticket-applying means to apply a ticket in timed relation to the winding operation.
7. In a winding machine, a spindle adapted to mount a bobbin thereon, means for rotating the spindle to wind yarn on the bobbin, means for applying an identification ticket to position it between the winding yarn strand and the bobbin to cause it to be gripped to the bobbin with one end projecting from the winding, and means for operating said ticket-applying means to apply a ticket in timed relation to the winding operation.
8. In a machine for packaging yarn, means for applying an identification ticket to each package wound on the machine, said ticket-applying means operating to insert the ticket between the winding yarn strand and the bobbin to cause the ticket to be gripped to the bobbin, and an electromagnet for operating said ticket-applying means.
9. In a machine for packaging yarn, means for applying an identification ticket to each package wound on the machine, said ticket-applying means operating to insert the ticket between the winding yarn strand and the bobbin to cause the ticket to be gripped to the bobbin, an elec-

tromagnet for operating said ticket-applying means, and automatically-operated means for controlling the energization of the electromagnet.

10. In a winding machine, means for winding a bobbin, means for applying an identification ticket between the winding yarn strand and bobbin to cause the ticket to be gripped thereby, an electromagnet for operating said ticket-applying means, an electric circuit for the electromagnet, a switch in the circuit, and control means for operating the switch in predetermined timed relation to the winding operation whereby to energize the electromagnet and apply a ticket to the bobbin.

11. A device for serving identification tickets from a continuous strip thereof comprising means for gripping the strip, means for moving the gripping means to feed the strip a distance equal to the length of a ticket, means for severing a ticket from the strip at the end of the feeding stroke, and resilient means for retaining the severed ticket projecting from the device.

12. A device for applying identification tickets to yarn packages from a continuous strip of tickets comprising reciprocable gripping means adapted to feed the strip during its movement in one direction and release the strip during its movement in the opposite direction, means for severing a ticket from the strip at the end of the operative stroke of the gripping means, and an electromagnet for reciprocating the gripping means a distance equal to the length of the ticket to be applied.

13. A device for applying identification tickets to yarn packages from a continuous strip of tickets comprising a reciprocable slide, a member mounted on the slide and having means cooperating therewith to grip the ticket-strip therebetween, means for operating said member to grip the ticket-strip and advance the slide in one direction and for operating the gripping member to release the strip and return the slide to initial position, and means on the slide operative to sever a ticket from the strip at the end of the advancing motion of the slide.

14. A device for applying identification tickets to yarn packages from a continuous strip of tickets comprising a reciprocable slide, a member mounted to rock on the slide and having means cooperating therewith to grip the ticket-strip therebetween, means for operating the member to cause it to grip the ticket-strip and reciprocate the slide, said slide and member being adapted to grip the strip in one direction of movement and release the strip in its opposite direction of movement, means for limiting the longitudinal movement of the slide, and cooperating cutting edges on said gripping member and slide for severing an individual ticket from the strip upon continued movement of the gripping member after the slide has reached the end of its longitudinal movement.

15. A device for applying identification tickets to yarn packages from a continuous strip of tickets comprising a reciprocable slide, a bell-crank member mounted to rock on the slide and having one of its arms adapted to cooperate with the slide to grip the ticket-strip thereto, a bifurcated operating member for engaging the other arm of the bell-crank member to rock the latter to grip the ticket-strip and advance the slide in one direction and to rock the member to release the strip and return the slide to initial position,

and an electromagnet for actuating the bifurcated operating member.

16. A device for applying identification tickets to yarn packages from a continuous strip of tickets, comprising a reciprocable slide, a bell-crank member mounted to rock on the slide and having a portion cooperating with the slide to grip the ticket-strip therebetween, cooperating edges on the member and slide for severing an individual ticket from the strip, means for controlling the rocking movement of the bell-crank member during its operative stroke to prevent a ticket from being severed from the strip, means for operating the bell-crank member to grip the ticket-strip and thereafter advance the slide, and means for limiting the longitudinal movement of the slide whereby continued movement of the bell-crank member by the operating means will cause the cooperating cutting edges to sever an individual ticket from the strip.

17. A device for applying identification tickets to yarn packages from a continuous strip of tickets comprising a reciprocable slide, a bell-crank member mounted to rock on the slide and adapted to cooperate therewith to grip the ticket-strip thereto, a bifurcated member embracing one arm of the bell-crank member and engageable with one side thereof to rock the bell-crank member to grip the ticket-strip and thereafter slide the slide, said bifurcated member being operative on the bell-crank member in the opposite direction to release the ticket-strip and return the slide to initial position, and an electromagnet for actuating the bifurcated operating member.

18. A device for applying identification tickets to yarn packages from a continuous strip of tickets comprising reciprocable gripping means having opposed members relatively movable toward each other for gripping the strip therebetween and away from each other to release the strip, operating means for positively moving the members toward each other to grip the strip therebetween and thereafter moving the gripping means bodily in one direction through an operative stroke, and means for severing a ticket from the ticket-strip at the end of the operative stroke of the gripping means, said operating means also acting to positively move the members away from each other to release the strip and thereafter move the gripping means bodily through a return stroke to initial position.

19. A device for serving identification tickets from a continuous strip thereof comprising means for gripping the strip, means for moving the gripping means to grip and feed the strip a distance equal to the length of a ticket, said gripping means including cooperating severing means, and means for operating the gripping means at the end of the feeding stroke to sever a ticket from the strip.

20. A device for serving identification tickets from a continuous strip thereof comprising a reciprocable slide, a member carried by the slide and having means cooperating therewith to grip the ticket-strip therebetween, said slide and gripping member having cutting edges, means for operating said gripping member to grip the ticket-strip and advance the slide, and means for operating the gripping member to sever a ticket from the strip at the end of the advance of the slide.
